T. F. CROCKER

TELEPHONE SYSTEM

1,776,653

Filed March 14, 1929

UNITED STATES PATENT OFFICE

THOMAS F. CROCKER, OF CHICAGO, ILLINOIS, ASSIGNOR TO RESERVE HOLDING COMPANY, OF CHICAGO, ILLINOIS, A CORPORATION OF DELAWARE

TELEPHONE SYSTEM

Application filed March 14, 1929. Serial No. 346,861.

This invention relates to telephone systems in general, but is concerned more particularly with trunk circuits and auxiliary equipment for connecting small private automatic telephone exchanges with central offices of various types.

The invention is especially adapted for establishing temporary trunk connections between a private automatic exchange, hereininafter referred to as a P. A. X., installed on a ship and a central office ashore. Naval vessels, and also ships of the merchant marine, are frequently equipped with a small P. A. X. for providing service between different stations aboard ship, such as the various officers' quarters, bridge, engine room, etc. The service provided is necessarily entirely local when the vessel is at sea. However, when the vessel is in port it is often desirable to establish a connection between the P. A. X. and a central office of the port, in order that business may be transacted by telephone with various establishments ashore.

Ships, as a rule, will put in at a number of different ports, and it is very probable that in the different ports different types of telephone systems will be in use. In order to meet these conditions to the best advantage, a connecting circuit should have a universal application; that is, it should be capable of being used with any of the types of telephone systems in general use, such as magneto and common battery manual systems and automatic systems.

Furthermore, since the call numbers of the P. A. X. stations will usually be unknown to the central office subscribers and operators, it is desirable that all calls from the central office to the P. A. X. be answered by an attendant who can then extend the call to the proper P. A. X. station. The attendants service will be required only when the ship is in port, and it will, therefore, probably be impractical to carry an especially trained attendant for this limited duty. Instead, the duty may be delegated to a seaman whose limited training makes it desirable that the routine of answering and completing calls be as simple as is practicable.

One of the main features of the invention

is the provision of a trunk circuit for use under the above described conditions which will operate satisfactorily with any of the commonly used types of central office equipment.

Another feature is the extreme simplicity of the attendant's equipment and the resultant simplicity of routine operations of answering and extending calls.

Another feature is the arrangement for giving the calling central office subscriber or operator a distinctive tone to indicate that the call has been extended to the P. A. X. This feature involves a novel means for generating the tone and for impressing it on the trunk in response to a call.

Another feature is the arrangement whereby the attendant controls the release of the P. A. X. equipment until the call is answered, whereupon the control is transferred to the called station.

The foregoing features, together with others not specifically mentioned, will be described in detail with the aid of the accompanying drawing, which discloses the invention by means of the usual schematic circuit diagrams and which shows sufficient equipment in a telephone system in which the invention may be employed so that its operation may be readily understood.

Referring now to the drawing, trunk equipment TR is individual to the trunk and associated therewith is the common equipment including night alarm apparatus NA, operator's telephone set OTS, and ring-back tone generator RBT. Line switch LS, also individual to the trunk, is an ordinary rotary type line switch whose wipers move only in a forward direction and have no normal or home position. Line switch LS, together with other similar line switches of the P. A. X., have access to the regular P. A. X. connectors such as C, which in turn have access to the various P. A. X. subscribers' lines of which that terminating in substation T is shown. Connector C may be of the same general type as the connector shown in Fig. 2 of United States Patent No. 1,175,119 to A. H. Blessing, issued March 14, 1916. Substation T is an ordinary automatic substa-

tion set comprising the usual talking, signaling, and impulsing instrumentalities.

The operation, briefly stated, is as follows: When a call from the central office is extended to the P. A. X. over the trunk, a signal at the attendant's position is operated. The ring-back tone apparatus is also operated and places a characteristic tone on the trunk to inform the calling subscriber or operator that the call has been extended. Upon noting the signal, the attendant answers by operating key K to the left, thereby establishing a talking connection with the central office subscriber or operator and disconnecting the ring-back tone equipment. After being informed as to whom the call is for, the attendant operates key K to the right and completes a connection to line switch LS in the P. A. X. The line switch further extends the connection to an idle connector such as C. The attendant then dials the number of the wanted P. A. X. station. The connector signals the wanted station in the usual manner and when the called station answers reverses battery back over the calling trunk. After dialing, the attendant restores key K to normal or may operate the key to the left to listen in on the trunk. The attendant must not hang up the receiver until the called station answers. When the connector reverses battery, an additional locking circuit for the trunk equipment is completed, thereby placing control of the release with the called station. When the attendant is assured that the call has been answered, the attendant's receiver may be replaced or other calls may be handled. When the called station disconnects, the locking circuit for the trunk equipment is opened and the equipment releases.

Having briefly described the operation and the apparatus involved, a detailed description of the operation will now be given. It will be assumed that a call is extended to the P. A. X. from a common battery manual central office. When the operator plugs in, a circuit is completed by way of the operator's cord circuit (not shown), conductor 2 of the trunk, upper left-hand winding of repeating coil R, upper winding of relay 11, condenser 4, lower left-hand winding of repeating coil R, conductor 3, back to the operator's cord circuit. The operator then projects ringing current out on the trunk, whereupon relay 11 operates and at armature 14 completes the locking circuit for its lower winding. This locking circuit may be traced as follows: battery, lower winding of relay 11, armature 14, resting contact of key K, winding of relay 51 to ground; and in parallel therewith by way of lamp L, upper and lower windings of relay 31 in series to battery. Relay 31 operates over the above circuit and at armature 33 short circuits its upper winding, thereby permitting lamp L to light. At armature 34 relay 31 also closes a circuit from battery by

way of armature 34 and its working contact to the night key which, however, is operated only when the attendant is absent from the position; the night key being normal, no action takes place. If the night key is operated, the buzzer will audibly signal the attendant.

Relay 51 also operates in series with relays 11 and 31 and at armature 56 completes a circuit for relay 52 including resistance 61. Relay 52 operates and at armature 57 closes a circuit for relay 53. Relay 53 is of the same general type as the relay shown in Fig. 1 of United States Patent No. 1,641,256 to J. Erickson, issued September 6, 1927. When its circuit is closed, relay 53 actuates its armature 58. Spring 64 is rigidly fixed at its upper end 65 and at its lower end is fitted with a weight 63. At the point between the fixed end and the weight is a small projection or contact 66 with which a corresponding contact on armature 58 engages when relay 53 is energized. The engagement of the two contacts starts spring 64 to vibrating as a pendulum with the axis at the fixed end 65. As armature 58 remains in actuated position, it tends to damp the vibrations of spring 64. The amplitude of the vibrations gradually decreases and the frequency gradually increases, the change in frequency being more marked as the amplitude approaches zero. The contacts between the armature and the spring remain closed for gradually increasing intervals with each cycle of vibrations.

The closure of the vibrating contacts completes a circuit for slow-acting relay 54. This relay has a high impedance and when its circuit is closed for very short intervals does not actuate its armature. When the closed circuit interval increases sufficiently, the relay energizes and maintains its armature in operated position for the remainder of the period of vibration of spring 64. At armature 59, the tone lead is connected to a point between the relay and the vibrating contacts and the remainder of the vibrations serve to produce a tone therein. These vibrations persist for a short time after relay 54 has operated and the tone produced is transmitted back by way of armature 59, condenser 55, armature 14, lower winding of relay 11 to battery.

Relay 54 also short circuits the winding of relay 52 at armature 60. Relay 52 which is also slow acting deenergizes after a short interval and opens the circuit of relay 53 which also deenergizes. The deenergization of relay 53 separates the vibrating contacts 66, thereby stopping the tone (assuming that the vibrations persist until relay 52 deenergizes) and also opening the circuit of relay 54. Relay 54 deenergizes, opens a point in the tone circuit at armature 59, and also removes the short circuit from relay 52. Relay 52 again

energizes and starts the cycle of operations as previously described as long as relay 51 remains energized.

As was previously stated, the upper and lower windings of relay 11 are inductively coupled. The tone current flowing periodically in the lower winding is induced in the upper winding which is bridged across the trunk. The subscriber or operator at the central office on hearing this tone, which is very similar to the ring-back tone commonly used in automatic telephone systems, is thereby informed that the call has been extended to the P. A. X.

On noting the lighted condition of lamp L, the attendant answers by lifting receiver RE from the switch-hook and by operating key K to the left, thereby connecting the receiver RE in telephonic connection with the trunk by way of the right-hand winding of repeating coil R. The operation of key K also places a short circuit around condenser 4 and relay 11 and around condenser 5, which closes a direct current path over trunk conductors to give the operator answering supervision and improve the transmission, and also opens the circuit of the lower winding of relay 11 and the ring-back tone equipment. Relays 11, 31, and 51 deenergize thereby stopping the operation of the ring-back tone apparatus and extinguishing lamp L. The attendant then converses with the central office operator or subscriber to determine the wanted party at the P. A. X. It will be noted that in removing the receiver from the hook a circuit was closed from the ground by way of the switch-hook, transmitter, right-hand winding of induction coil IC, winding of relay 32 to battery. Relay 32 operates and at armature 35 closes a circuit to the trunk equipment, the utility of which will be described later on.

After ascertaining the number or the name of the P. A. X. subscriber wanted, the attendant operates key K to the right, thereby closing an obvious circuit for the lower winding of relay 13, disconnecting the talking leads from the repeating coil and closing a circuit for calling device CD. Relay 13 operates and at armature 18 closes a locking circuit for its lower winding, including armature 35 of relay 32. At armature 19 a circuit is closed for the upper winding of polarized relay 12, which does not operate, however, over its upper winding alone. At armatures 16 and 20 calling device CD is bridged across the trunk conductors leading to line switch LS, the circuit of which may be traced as follows: battery, winding of relay 72, armature 74 and its resting contact, armature 16, upper right-hand operated contact of key K, contacts of calling device CD, lower right-hand operated contact of key K, armature 20, armature 76 and its resting contact to ground. Relay 72 operates over the above-traced circuit and at armature 77 completes a circuit

for relay 71 and motor magnet 73 in series and at armature 78 connects test wiper 81 to the junction of relay 71 and the motor magnet. In case the wipers of the line switch are standing on a busy trunk, wiper 81 will find a ground. An operating circuit for the rotary magnet may be traced from ground, wiper 81, armature 75 and its resting contact, armature 78, interrupter springs, winding of rotary magnet 73 to battery. Rotary magnet 73, on operating, opens its own circuit at the interrupter springs and on deenergizing steps the wipers ahead to the next set of contacts. This cycle of operation is repeated as long as wiper 81 encounters a grounded contact. Relay 71 is prevented from operating at this time, being shunted out by the ground on the test wiper. When an idle contact is found, wiper 81 will not encounter a ground, and relay 71 will, therefore, operate over the previously traced circuit including the winding of rotary magnet 73. The rotary magnet, however, will not operate in series with relay 71, due to the high resistance of that relay. Assuming that the trunk comprising conductors 82-84 leading to connector C is the idle trunk selected, relay 71, on operating, connects the impulsing circuit through by way of armatures 74 and 76 and their working contacts, wipers 79 and 80, conductors 82 and 83, to the line relay of connector C. Relay 71 also disconnects the test wiper from the junction with the rotary magnet and connects it in series with the relay 71 so that when the connector returns a ground over the release trunk, relay 71 will remain locked in operated position.

Relay 71 also disconnects relay 72 from the trunk, and this relay, being slow acting, will maintain its armatures in operated position for a short time thereafter, providing a holding ground for relay 71 until the connector has had time to return the holding ground over the test wiper. The attendant now dials the digits of the called P. A. X. station, operating connector C in the usual way to step its wipers 85-87 into engagement with the calling line which will be assumed to be that comprising conductors 91 and 92 extending from substation T and terminating on contacts 88 and 89. The connector signals the called station in the well-known manner, and when the called subscriber answers reverses battery back over the trunk in the usual manner.

After dialing the digits of the wanted station, the attendant will restore key K to normal or operate it to the left. The calling device CD is then disconnected from the trunk and the holding circuit for the line switch is transferred to the loop including the right-hand windings of repeating coil R and the lower winding of polarized relay 12. Relay 12 does not operate at this time, as battery flows in the lower winding in such a direction

4
that the two windings oppose each other. When the called station answers, the connector reverses battery as previously mentioned, and, the current flow being reversed in the lower winding of polarized relay 12, the two windings assist each other and relay 12 operates. Relay 12 closes a holding circuit for the upper winding of relay 13 at armature 15. The attendant will normally throw key

19 K to the left and listen in on the trunk until the called party answers or, if there are other calls to be attended to, key K may be restored to normal and the other calls attended to. When the attendant is assured that the called station has answered, receiver RE may be replaced on the switch-hook, whereupon the circuit of relay 32 will be opened and that relay deenergized. Relay 32 at armature 35 opens the holding circuit for the lower winding of relay 13, which, however, remains locked up over its upper winding under control of relay 12. At the termination of the call the subscriber at substation T will replace the receiver, thereby opening the called line loop. Connector C will reverse battery over the trunk back to normal and relay 12 will deenergize and open the circuit of relay 13. Relay 13 will then deenergize and open the holding loop to the line switch, thus releasing the line switch and the connector in the usual manner. The equipment in the P. A. X. will restore to normal and will be immediately available for another call. The central office subscriber or operator is thus unable to hold up the connection in the P. A. X. It will be noted that the P. A. X. equipment will not release until the attendant's receiver is replaced on the switch-hook.

40 In the foregoing description it was assumed that the call was extended from a common battery manual central office. It is obvious that similar calls may be extended from magneto manual central offices or from automatic central offices, the only requirement being that ringing current be projected on the trunk. It is also obvious that the attendant will not be required to learn any complicated method of operation or be required to watch a confusing number of supervisory signals.

45 Having described the invention, that which is considered new and is desired to have protected will be pointed out in the appended claims:

50 **What is claimed is:**

1. In a telephone system, an incoming trunk, at attendant's position, means for extending a call over said trunk to said position, automatic switches, means controlled by the attendant for further extending the call over said switches, means controlled by the attendant for maintaining said switches in operated position, and means operative responsive to the call being answered for maintaining said switches in operated position inde-

pendent of said attendant controlled means.

2. In an automatic telephone system of the type in which incoming calls are intercepted by an attendant, means controlled by the attendant for further extending a call over the regular exchange equipment to a called station, and means effective when the call is answered for transferring control of the release of the connection to the called station. 70

3. In a telephone system, an incoming trunk, a relay having two inductively coupled windings one of which is bridged across the conductors of the trunk, a locking circuit for said relay including the other winding, means for operating the relay responsive to the extension of a call over the trunk, means for closing said locking circuit responsive to the operation of the relay, and means for impressing a characteristic tone on said trunk via said locking circuit and the inductively coupled windings of said relay. 75 80 85

4. In a telephone system, a two-conductor trunk line, a double wound relay having one winding bridged across the conductors of said trunk line, a locking circuit for the relay including the other winding thereof, and means for intermittently connecting a tone source to said locking circuit whereby a tone is inductively applied to the trunk line. 90

5. In a telephone system, a two-conductor trunk line, a double wound relay having one winding bridged across the conductors of said trunk line, means controlled over the trunk line for operating said relay, a second relay, means controlled by said first relay for completing a holding circuit for its other winding and said second relay in series, and means controlled by said second relay for intermittently connecting a source of tone to said holding circuit. 95 100 105

6. In a telephone system, a two-conductor trunk line terminating in an operator's position, a double wound relay having one winding bridged across the conductors of the trunk line, a signal at said position connected in parallel with the other winding of said relay, means for operating said relay responsive to the extension of a call over the trunk line, means controlled by said relay for completing a circuit for its other winding and for said signal, means for intermittently connecting a source of tone to said circuit whereby a tone is intermittently applied to the trunk line, means for answering the call, and means responsive to the answering of the call for opening said circuit to disable said signal and to disconnect said tone source. 110 115 120

7. In a telephone system, a trunk line extending through an attendant's position to an automatic switch, a telephone set at the position rendered effective responsive to the removal of the receiver from the switch-hook, means for connecting said set to the trunk line to answer a call thereon, means controlled by the attendant for operating said switch to 125 130

further extend the call to a called subscriber, and arrangements whereby the attendant is required to keep the receiver off the switch-hook until the called subscriber answers in order to prevent the release of said switch.

5 In witness whereof, I hereunto subscribe my name this 12th day of March, A. D. 1929,
THOMAS F. CROCKER.
